RESISTANCE ELEMENT

Karl M. Lederer, Newark, and Alexander Dempster, Linden, N. J., assignors to Weston Electrical Instrument Corporation, Newark, N. J., a corporation of New Jersey

Application April 20, 1936, Serial No. 75,446

9 Claims. (Cl. 201—67)

This invention relates to resistance elements and particularly to resistor bulbs for use in the electrical measurement of temperatures.

The resistor bulbs for temperature measurements are small units which may be secured to an object, such as an engine or carburetor, for obtaining a continuous measurement of temperature by observing the variation of current flow through the resistor bulb as the resistance thereof varies with temperature. The small size of these units has made it difficult to obtain good electrical insulation and a good heat transfer to an enclosed resistance winding.

An object of this invention is to provide an enclosed resistance element which is adequately insulated from its support and an enclosing shell, and which responds rapidly to temperature changes at the exterior of the shell. An object is to provide a resistor bulb in which a bare resistance wire is insulated from its metallic support by a thin layer of metallic oxide that is formed upon the metallic support. Another object is to provide a resistor bulb in which the resistance wire is formed as a relatively short length of a single layer coil of small diameter and small pitch, and this short length of closely coiled wire is wound on the grooved surface of a supporting tube. More particularly, an object is to provide a resistor bulb of the type including a mounting head carrying a tubular shell or container within which the resistance is located, the resistance being a bare wire wound upon a grooved aluminum tube that carries an insulating film of aluminum oxide.

These and other objects and advantages of the invention will be apparent from the following specification when taken with the accompanying drawing in which:

Fig. 1 is an enlarged longitudinal section through the mounting head and shell of one embodiment of the invention, other parts being shown in elevation, and a portion of the connecting cable being also shown;

Fig. 2 is a similar sectional view, at right angles to Fig. 1, of the insulating spool and the resistance element of the resistor bulb;

Fig. 3 is a plan view of the insulating spool and the terminal plugs mounted thereon;

Fig. 4 is a fragmentary sectional view, on a still larger scale, through the lower end of the resistor bulb; and

Fig. 5 is a fragmentary sectional view through another embodiment of the invention.

In the drawing, the reference numeral 1 identifies the central enlarged section of the mount-

ing head of the resistor bulb, this section being of hexagonal form or provided with grooves or recesses for taking a wrench by which the adjacent threaded section 2 of the head may be threaded into an opening in the water jacket or oil case of an engine, into the wall of a carburetor air inlet, or into any other object or fluid container where temperature measurements are desired. The threaded section 2 merges into a thin-walled shell 3 that is closed at its lower end. The upper end 4 of the mounting is a threaded sleeve which receives the bushing 5 by which the connecting plug 6 of a cable 7 may be secured within the sleeve 4 of the resistor bulb. Metallic sleeves 8 within the plug 6 are provided with screws 9 at their outer ends for securing the cable wires to the sleeves, and the lower ends of the sleeves have a close sliding fit upon the friction plug terminals 10 of the resistance element.

The plug terminals 10 extend through a spool 11 of insulating material, preferably a ceramic material if the resistance bulb is to be used at elevated temperatures, which is retained within the mounting head by a split ring 12. A vent opening 13 extends through the mounting head at the level of the upper surface of the spool 11 to prevent accumulations of oil or moisture adjacent the plug terminals 10. This vent is important in many instances as the outer ends of the resistor bulbs are frequently so located that oil or water may seep into the mounting head and affect the insulation of the terminals.

A thin tube 14 is cemented or otherwise secured to the lower reduced diameter portion of spool 11, and extends to or approximately to the lower end of the shell 3. The lower portion of the tube 14 has a double helical thread or parallel grooves formed in its outer surface and the winding 15 of resistance wire is located within these grooves. The lower end of the tube has two adjacent notches 16 which provide an anchor for the central portion of the winding, see Fig. 2.

As best shown in Figs. 4 and 5, the resistance wire is first formed into a close coil or single layer solenoid of small diameter and small pitch, thus substantially reducing the effective length of the winding which is to be placed upon the tube. This reduction in length is particularly advantageous when the winding is looped back upon itself and formed as a "dual" winding to place both terminals at the upper portion of the tube. The actual length of the resistance wire is several feet but the close coiling may reduce this to an effective length of less than one foot of winding material that is to be placed within the

grooves of the tubular support. It is possible, of course, to apply the resistance wire in the customary form of a simple single layer helix and this type of winding will be quite satisfactory in the case of low resistance units.

The upper uncoiled ends 15' of the resistance wire 15 are secured beneath, clamped, welded or soldered to washers 17 on screws 17' which are insulated from tube 14 and thread into the lower extension 10' of one of the connecting terminals 10 and into a similar extension 18' on a stub terminal 18.

The resistance wire 15 will usually be a copper wire as the temperature measuring systems are customarily graduated in degrees corresponding to the temperature-resistance variations of copper. When the entire resistance is provided by the wire 15, the stub terminal 18 is directly connected to a terminal lug 19 on the second connecting terminal 10. It is desirable, however, to form the resistance 15 of a material, such as nickel, having a higher resistance than copper. This permits the use of a larger size or a shorter length of the nickel resistance wire, but a compensating winding of wire having a substantially zero temperature-resistance characteristic must be used with a nickel wire resistance if the resistor bulb is to be interchangeable with the standard copper wire resistances. This compensating winding 20 of manganin is wound upon the spool 11 and connected between the stub terminal 18 and the terminal lug 19. As described and claimed in the copending application of Karl M. Lederer, Ser. No. 75,441, filed April 20, 1936, the characteristics of a standard copper wire resistor bulb having a resistance of 100 ohms at 25° C. may be obtained when the nickel wire 15 has a resistance of 65 ohms at 25° C. and the manganin wire 20 has a resistance of 35 ohms.

The clearances between the tube 14 and the shell 3 are preferably held to minimum values to provide a good heat transfer between the exterior of the shell and the resistance wire, but greater clearance is provided between the upper end of tube 14 and the mounting sleeve 2 and avoid a heat transfer at this section. It is possible to form the tube 14 of a molded plastic and to use a thin insulating sleeve 21 of the same material when a bare wire 15 is used, and the resistor bulb will not be subjected to high temperatures. The mounting head and integral sleeve 3 may be formed of steel or Monel metal, brass, or aluminum alloys as 17-ST, XA-11S-T, etc.

Preferably, however, the tube 14 and the sleeve 21 are formed of aluminum that has been treated by known electrolytic processes to form a substantially continuous insulating film of aluminum oxide on and in situ from the metal at those parts which contact or may contact with the bare resistance wire 15. This insulating film is so thin that it cannot be shown in Figs. 1 and 2, but it is shown in the enlarged scale view, Fig. 4, as a coating 14a on the aluminum tube 14 and a coating 21a on the inner surface of the aluminum sleeve 21. This view is not to exact scale, however, as the thickness of the oxide coating has been exaggerated for clearness of illustration. The pitch of the closely coiled wire 15 is, of course, substantially greater than the diameter of the bare wire to prevent short-circuiting of adjacent turns.

As shown in Fig. 5, a simpler construction may be provided when the design requirements are such that the shell itself may be of a metal that

can be oxidized to supply the layer of insulation about the resistance winding. The shell 3' may be formed of an aluminum alloy under these conditions, compositions known as 17-ST and XA-11S-T having high strength, good machining characteristics, and being susceptible to treatment to form a film of aluminum oxide 3a on the inner surface of the shell for insulation of the bare wire 15. The integral mounting head and shell construction of Fig. 1 may be employed, or alternatively, the aluminum shell 3' may be secured to a steel mounting head. Where conditions permit, the vacant space in the grooves may be filled either with a material 15" such as powdered asbestos, plaster of Paris or grease and Vaseline as thereby the heat response and insulation will be improved materially.

As shown in Fig. 1, one or more passages 22 may be formed in the mounting head 1 to receive a wire that may be secured to a stud on the engine by a lead seal to prevent an unauthorized removal of the resistor bulb.

The material and form of the tube 14, and the shell 3 affect the heat transfer and the response of the resistor bulb and, so far as is practical, the thickness of these parts should be reduced to a minimum. As an example, it may be stated that a wall thickness for tube 14, between the grooved winding section and the support spool 11, of about 0.010 inch, with a wall thickness of about 0.015 inch for the housing shell 3, has been found satisfactory for general conditions of use. The grooved section which carries the resistance wire should preferably be spaced at least one-half inch from the mounting head and threaded sleeve 2 to reduce the heat transfer between the mounting head and the wire.

Attention is directed to the fact that a somewhat simpler terminal construction may be employed when the entire resistance is provided by the winding 15. Each terminal plug 10 may then have the extension 10' for connection to the winding 15 when the compensating winding 20 is not used. The assembly operations are somewhat simpler and the resistance wire is more securely sealed when the mounting head and shell 3 are formed in one piece.

We claim:

1. A resistor bulb for the electrical measurement of temperature comprising a metallic support, a resistance wire of relatively high temperature coefficient of resistance wound on said support, a film of non-conducting metallic oxide on and formed from the metal of said support, a shell in heat transfer relation to said resistance wire and enclosing said support and resistance wire, means for supporting said shell in heat transfer relation to the material whose temperature is to be measured, and a substantially continuous film of non-conducting metallic oxide within said shell and insulating the resistance wire therefrom.

2. A resistor bulb for the electrical measurement of temperatures comprising a thin-walled tubular aluminum support, a bare resistance wire of relatively high temperature-resistance coefficient wound on said support, a non-conducting aluminum oxide film on and formed from the metal of said support to insulate the wire therefrom, and a thin-walled shell in intimate heat transfer relation to said wire and closely enclosing said support and wire, whereby said wire quickly assumed the temperature of the medium surrounding said shell and its resistance thereby fluctuates as a function of that temperature.

3. A resistor bulb for the electrical measure-

ment of temperatures comprising an aluminum tube having a helically grooved surface, a bare resistance wire of finite and predetermined temperature-resistance characteristic wound upon said tube in the grooved surface thereof, a non-conducting film of aluminum oxide on and formed from the metal of said tube to insulate the wire therefrom, a metallic shell enclosing said tube and in intimate heat transfer relation to the wire thereon, means for mounting the shell on and in good heat transfer relation to an object whose temperature is to be measured, and insulating means comprising a substantially continuous film of aluminum oxide separating said wire from said shell.

4. The invention as claimed in claim 3, wherein said insulating means includes an aluminum sleeve surrounding said winding of resistance wire and the adjacent portion of said tube, the interior surface of said sleeve having an adherent oxidized surface constituting said film of aluminum oxide.

5. The invention as claimed in claim 3, wherein in the portion of said shell adjacent said resistance wire is aluminum, and the film of aluminum oxide insulating the same from the winding is an adherent layer on the interior of said portion of the shell.

6. A resistor bulb having a resistance that varies as a predetermined factor of its temperature for use in the electrical measurement of temperatures, said resistor bulb comprising a tubular aluminum member having a layer of aluminum oxide formed in situ on the exterior surface thereof, said member having a thin wall and being helically grooved at the exterior of one end portion thereof, and a multiple turn winding of closely coiled bare resistance wire in the grooves and entirely within the exterior surface of said member, adjacent coils of said wire and adjacent turns of said winding, respectively, being spaced from each other.

7. In a resistor bulb, a hollow mounting head terminating in a shell having a closed inner end, a spool of insulating material within the said head, a pair of connecting terminals on said spool for making connections to an external circuit, a 5 stub terminal on said spool, a temperature-variant resistance having the ends thereof connected to said stub terminal and one of said connecting terminals, means supporting said resistance within the inner end of said shell and closely adjacent the circumferential wall thereof, and a 10 temperature-invariant resistance on said spool, the ends of said temperature-invariant resistance being connected to said stub terminal and to the second of said connecting terminals. 15

8. A resistor bulb as claimed in claim 7, wherein supporting means comprises a tubular member carried by said spool and having the temperature-variant resistance wound on the exterior surface thereof, and the said stub terminal and 20 the first of said connecting terminals extend into said tubular member.

9. In a resistor bulb, the combination with a tube having a resistance wire thereon and insulated therefrom, of a mounting head having an 25 externally threaded sleeve projecting from one side thereof, said sleeve terminating in an integral tubular shell, said shell having a closed inner end, a threaded sleeve integral with and projecting from the other side of said mounting head 30 for receiving a cable plug, a passage extending through said head to connect the bores of said sleeves, a disk of insulating material secured in said passage and supporting said tube within said shell, and terminals for said resistance wire supported by said disk within the second sleeve for engagement with complementary terminals on a 35 cable plug.
